UNITED STATES PATENT OFFICE.

JOSEPH BULOVA, OF NEW YORK, N. Y., ASSIGNOR TO BULOVA WATCH COMPANY,
INC., OF NEW YORK, N. Y., A CORPORATION OF NEW YORK.

WATCH-MOVEMENT GUARD.

Application filed July 16, 1925, Serial No. 43,965. Renewed November 17, 1927.

Among the principal objects which the present invention has in view are:

To provide a guard positioned to prevent admission of foreign matter to the works 5 of the watch; to provide a novel and improved watch movement guard adapted completely to enclose the movement; to provide an improved guard of this character wherein the movement may be inspected 10 without removing the guard therefrom; to provide an improved guard for a watch movement having means for frictional engagement with the movement.

Drawings.

15 Figure 1 is a vertical section through a watch casing and movement guard with the watch movement shown in elevation;

20 Figure 2 is a vertical section through a watch casing with the movement guard positioned therein and shown in elevation;

Figure 3 is a perspective view of the guard;

25 Figure 4 is a fragmentary sectional view corresponding to Figure 1 and illustrating a modified form of the invention;

Figure 5 is a fragmentary perspective partly in section of the movement guard shown in Figure 3;

30 Figure 6 is a fragmentary section illustrating the connecting engagement between elements of the guard.

Description.

35 The guard of the present invention is designed for employment in connection with small and delicate wrist watches and watches of the ornamental type, wherein it is desired to construct a watch in a minimum of space. In the ordinary construction of such watches the movement is constructed upon a plate 10 on which are mounted the necessary springs and gears the whole forming a unitary construction.

40 The movement as a unit is disposed within a section 11 of the watch casing which section is adapted to receive thereover a back or closure portion 12 in tight fitting engagement to form the watch casing. The

45 front section 11 is provided with an internal flange 12a adjacent its periphery carrying a watch crystal 13 which is extended over the hands 14 operating over the dial 15 of the watch movement 10, forming the face of

50 the watch. As is usual in the construction

of these watches the plate 10 is provided with a marginal recess 16 adjacent the spindle 17 of the winding stem for the watch.

In the ordinary construction of this type of watch, it has been found that dirt and 60 foreign matter enters the watch movement through the recess formed in the plate 10 of the movement, even though disposed within the watch casing. This objectionable feature is eliminated in the present invention by the provision of a movement guard 65

18 formed of metal or other suitable material substantially in the shape of a truncated inverted cone to provide an annular open ended casing section. One end, such as the 70 larger end of the guard 18 is offset and provided with an upstanding flange 19 which is adapted to be bent internally over the offset shoulder 20 to engage over and retain a sheet of glass, celluloid or other transparent material 21. The connection between these elements is illustrated in Figure 6 75 wherein the flange 19 is shown in upright position and in engaged or fastening position. The offset shoulder 20 forming part 80 of this construction seats over the end or edge of the casing section 11 and affords means for withdrawing the guard ring through the open end of this casing section, by inserting a blade or the finger nail between the shoulder and the casing section. The movement may come away from the 85 casing section with the guard ring, or if it should remain in the casing section it would be freely movable.

90 In application the guard 18 is applied over the rear of the watch movement 10 with its lower rim 22 resting upon the overhang of the movement plate, the restricted contracting sides of the guard frictionally engaging over the walls of the movement plate as clearly illustrated in Figure 1 while the sides at the larger end frictionally engage the casing 11. The lower edge 22 of the guard is provided with a depending flange 95 23 adapted when in position to engage over and close the recess 16 in the movement plate. Adjacent the flange 23 the wall of the guard is apertured as at 24 to receive in close fitting engagement the stem 17 of the 100 winding spindle therethrough.

105 In a watch construction of the type herein exemplified the stem spindle 17 is held engaged with the movement by means of an internal detent controlled by a minute 110

set screw (not shown). In order to provide for access to the detent holding screw, the transparent member 21 is provided with a small bore 25 extending therethrough adjacent the spindle aperture 24 whereby access may be had to the detent operating screw.

In the modified construction illustrated in Figure 4 the guard 18' is substantially cylindrical conforming to the shape of the watch movement 10, and is provided with a laterally offset cylindrical portion 26 having an inturned flange 27 for engagement thereunder of a transparent movement cover plate 28. In this modification the guard portion comprising the enlargement 26 engages against the wall of the casing section 11 binding the movement and the guard in position.

20 Claims:—

1. In a watch, a casing section open at one end, a unitary movement disposed within said casing section, an annular open ended guard member surrounding said movement, said guard member being angled

intermediate its ends for frictional engagement at one end with said movement and for frictional engagement at the other end with said casing section, said casing section engaging end of the guard member having an 25 outward flange formed therein for seating over the open end of said casing section, an inturned terminal on said flange, and a movement cover member retained on said guard member beneath said inturned flange. 30

2. In a watch, a casing section open at one end, a unitary movement disposed within said casing section, an annular open ended guard member surrounding and frictionally engaging said movement and 35 adapted to be withdrawn through the open end of said casing section, said guard member having an outward flange formed to overlie the open end of said casing section and affording means for withdrawing said 40 guard member, an inturned terminal on said flange, and a movement cover member retained on said guard member beneath said inturned flange.

JOSEPH BULOVA.
